ALBERT J. ALLISON, OF DAYTON, OHIO, ASSIGNOR TO THE A. A. SIMONDS & SON COMPANY, OF DAYTON, OHIO, A CORPORATION OF OHIO.

BEATER-ROLL.

1,318,950.

Specification of Letters Patent. Patented Oct. 14, 1919.

Application filed February 25, 1919. Serial No. 279,161.

To all whom it may concern:

Be it known that I, ALBERT J. ALLISON, residing at Dayton, county of Montgomery, and State of Ohio, have invented certain new and useful Improvements in Beater-Rolls, of which the following is a full, clear, and exact description.

My invention relates to the class of beater rolls, wherein the fly bars are secured to the roll by resilient clamping devices. The first of this class of rolls was disclosed in my Patent No. 1,273,982, issued July 30, 1918, wherein an embodiment of the principle was broadly claimed. In my application now pending, Serial No. 233,791, filed July 21, 1917, I have disclosed another embodiment of the principle, which is an improvement over the first in that each bar is secured to the roll by a separate clamping device that permits any bar to be removed and replaced without loosening or in any way disturbing the other bars in the roll. In the present invention I provide for securing the bars either in pairs or singly. When secured singly any bar can be removed and replaced without disturbing any of the other bars; in the construction where they are secured in pairs there is a single fastening device at each end of each pair of bars, each device securing one end of both bars. Provision is made for equalizing the tension on the bars of a pair so that both will be held by an equal tension.

Whether secured singly or in pairs, the securing means is a clamping element or lever partaking of the nature of a beam supported at two points, with the bar or bars attached to the beam at a third point, the beam being put under a strain which reflects it more or less, so that the bar is held to its seat by the resiliency of the beam.

Although my invention is intended, primarily, for use in building new beating engines, it is peculiarly adapted to use in old rolls of certain types. In one of these types, one in very common use, the ends of the fly bars are notched and are secured to the roll by iron rings heated and dropped into the circle of notches, the ring being expected

to shrink and draw the bars tightly to their seats, which are usually slots formed in the periphery of the roll heads. Because of imperfections and inequalities in the parts it commonly happens that one or more of the bars are held but lightly, or maybe not at all, by the rings, with the result that they soon get loose in the slots and, becoming crystallized, break off, sometimes doing great damage to the machinery. Without other changes than replacing the old bars by new ones, or even using the old bars in some cases, these old rolls can be equipped with my improvement and endowed with all of the advantages it possesses. The form of device by which the bars are secured in pairs has all of the merits of the single device, besides being far less expensive. It is preferable, therefore, to build rolls with an equal number of bars. Among old rolls an uneven number of bars is often found, in which case one bar can be secured singly and the remainder in pairs. If for any reason it is found expedient to do so two or more of the bars may be secured singly and the remainder in pairs.

In the accompanying drawings,

Figure 1 is a longitudinal section of a roll equipped with my improvement, showing the type wherein the bars are secured in pairs.

Fig. 2 is a portion of a transverse section on line 2 of Fig. 1.

Fig. 3 is a fragmental view looking between two fly bars toward the shaft.

Fig. 4 is a longitudinal section of a roll equipped with a modified form of my device for securing the bars in pairs.

Fig. 5 is a portion of a transverse section on line 5 of Fig. 4.

Fig. 6 is a portion of a transverse section on line 6, Fig. 4.

Fig. 7 is a longitudinal section of a roll equipped with the type of device for securing the bars singly.

Fig. 8 is a part of a transverse section on line 8, Fig. 7.

Fig. 9 is part of a transverse section on line 9, Fig. 7.

Fig. 10 is a fragmental view looking in between the bars toward the shaft.

Fig. 11 is a longitudinal sectional view of one end of a roll showing another modification of my invention.

Referring now to Figs. 1, 2 and 3, the roll comprises a shaft 25 on which are rigidly fixed two heads 26, having inwardly extending flanges 27. The perimeter of the heads is provided with seats for the fly bars 28, in the present case slots 29. Each of the bars is pierced near its inner edge a short distance from each end to provide apertures for bosses or trunnions 30 projecting from each side of levers 31. In assembling the rolls two bars are placed in juxtaposition with a lever 31 between them at each end and the trunnions in the apertures. With the levers rocked to a position where they will be clear of the flanges 27 as at A in Fig. 1 the bars are dropped into their respective seats. Each lever carries a set screw 32 at its head end which when the lever is in its normal position abuts the inside of the flange 27. When the lever is in the position shown at A this set screw can be turned in or out so that the lever will lie in the desired position when the end of the screw rests on its abutment, the screw being finally secured against movement by a jam nut 33.

As an abutment for the tail end of the lever I provide a yoke 40, carrying a set screw 41, the end of which stands in a socket 42 in the tail end of the lever. The yoke comprises a cup shaped member 43 capable of passing between the fly bars, and a cross piece, or the yoke proper, which lies cross-wise and bears against the inner edges of the two bars. After the position of the lever has been fixed the yoke is let down between the bars with the cross piece turned endwise, as at B, Fig. 1, the end of the set screw 41 entering the socket. The yoke is then rotated one fourth of a turn, bringing it crosswise under the bars, and is held in this position while the set screw is screwed down, which raises the yoke up against the bars and bears down on the tail end of the lever. The ends of the cross piece are provided with lugs 44 which lie at the outsides of the bars, and together with the member 43 lying between the bars and the set screw in the socket form an interlock which prevents the tail end of the lever from becoming disengaged from the bars. The heads of the set screws 41 have transverse holes in which cotter pins 45 are inserted, said pins lying in notches 46 in the rim of the cup 43 and preventing movement of the screw. The sockets may be filled with a mixture of graphite and white lead to prevent corrosion at this point where acidulated water might accumulate and stand.

The lever 31 is in the nature of a beam supported at its ends, with a load concentrated at a point intermediate its ends. Screwing down the set screw 41 flexes the lever more or less and puts a tension on the lateral projection which carries the trunnions 30, this tension drawing the bars firmly to their seats. The resiliency of the lever maintains this tension constantly notwithstanding changes in conditions which might relax tension obtained by other means. For example: in the present case the fly bars are tapered in cross section, which makes flaring slots necessary in the heads, it being desirable that the bars fit rather snugly in the slots. In case a bar is too snug it might not go at once to the bottom of the slot, but do so later on. It is not to be understood that I expect my device to care for a large slip of this nature or of any other kind. But because of the deflection of the levers and their resiliency, a small readjustment or settling of the parts may occur without their becoming loose or their efficiency in any way impaired, where if they were secured by means which did not provide such a reserve of clamping power; e. g., by bolts acting directly on the bars and reacting directly on the heads, they might become lose. In fact, experience has shown that clamping devices which do not have this reserve power are not reliable. Another factor in the stability of the clamping power of my device is its ability to equalize the strain on the two bars. Both abutments for the lever being substantially mere points, acting in a common plane midway between the bars, the lever is able to rock one way or the other until both trunnions carry an equal strain. Another factor which is to be noted is the resiliency of the bars themselves. The extent to which this factor comes into play will depend on the relative rigidity of the bars and clamping elements.

In Figs. 4, 5 and 6 the roll comprises the same shaft 25, heads 26, flanges 27, bars 28, slots 29, trunnions 30 and levers 31, except that the levers do not have the set screws at their head ends or sockets at their tail ends. In place of the former I tap holes 50 and screw set screws 51 into the flanges 27. At the tail ends I provide yokes 52 which are pivotally attached to the levers. The bars are assembled in pairs with levers between them and dropped into their seats in the manner already described, the levers being rocked to a position where their head ends will clear the flanges 27, as at A. Then the levers are rocked to a position about as B, which permits the yoke, which has meanwhile been turned lengthwise of the lever, to be turned cross-wise. The screws 51 are then screwed down until the yoke bears against the lower edges of the bars

and the desired strain is put upon the levers. While this type of clamp may be preferred in some cases, the one shown in Figs. 1, 2 and 3 is preferable where an old roll is being modified, because the work will generally be done in a place where the facilities for drilling the holes 50 are not good. Therefore it is preferable to do the drilling in the factory, which can be done where the 10 clamps carry the set screws.

In Figs. 7 to 10 inclusive is shown the device for securing the bars singly. This structure again comprises the shaft 25, heads 26, flanges 27, fly bars 28 and slots 29. The levers I will now designate by the numeral 60 and they are provided with bosses 61 and 62 which extend into suitable apertures in the bars. Inasmuch as the strain is not balanced in this structure as it is 15 in the two previously described structures, I secure the levers to the bars by cap screws 63 screwed into the bosses 61. In assembling the roll a bar is set in place, and then 20 the lever is put in place and secured with the cap screw. Then by means of the set 25 screws 64 the desired strain is put upon the levers, the effect of which is the same as has been described. That is, the lever is in effect a beam resting at both ends and carrying 30 a concentrated load intermediate its ends, at the lug 61. The lugs are made loose enough in the apertures so the lever can function in the manner described. The set 35 screws 64 have extensions 65; I drive the usual wood fillers 66 between the bars, providing suitable holes through which the screws pass, and give additional security to the fillers by screwing nuts 67 on the ends of the screws.

Reverting to Figs. 5 and 6, it will be seen that the left hand bar in each of these figures is secured by the single device I have just described, the remainder of the bars being secured in pairs. It is evident that the 40 form shown in Figs. 1, 2 and 3 can also be used in connection with the single device in equipping rolls which have an uneven number of bars. The heads 26 shown in the present application are of the type commonly 45 used in rolls whose fly bars are secured by iron rings shrunk on the ends of the bars,—previously referred to—and since this type of head lends itself excellently to the use of my improvement I have employed it in the 50 present illustrations. It is evident, however, that this type of head is not essential to its success. Other structures which afford proper support for the bars and suitable 55 abutments for the clamping elements can be used with equal success. One of the advantages of my improvement is that the bars are secured by means within the roll, thereby 60 permitting the exterior of the roll to be smooth and free from projections or depre-

sions which might catch and retain parts of 65 the paper pulp.

In Fig. 11 I show a structure in which a disk 70 is mounted on the shaft 25, and instead of abutting the bars the tail end of the lever 71 is drawn down to or toward the 70 periphery of the disk by a screw 72.

While I have disclosed the preferred embodiment of my invention, and three modifications thereof, it is not to be supposed that I consider that these exhaust the possibilities 75 of variation within the scope of my claims, as they evidently do not.

What I claim is as follows:

1. In a beater roll, supporting elements carrying abutments and seats for fly bars; 80 fly bars occupying said seats, clamping elements secured to the bars and comprising resilient members which bear on said abutments, the abutting parts comprising set screws whereby pressure may be applied to 85 the clamping elements, thereby holding the bars firmly to their seats.

2. In a beater roll, supporting elements carrying abutments and seats for fly bars; 90 fly bars occupying said seats; clamping elements secured to the bars and comprising members which bear on said abutments, the bearing points of said abutments being set screws whereby pressure may be applied to 95 the members that bear thereon to clamp the bars to their seats.

3. In a beater roll, supporting elements carrying abutments and seats for fly bars; a pair of fly bars seated thereon, a clamping element comprising a lever having a trunnion extending from each side, one of said trunnions entering an aperture in each bar, the lever being thus enabled to rock so as to bring its head end under one of said abutments, a yoke which spans the bars and acts 105 as an abutment for the tail end of the lever; and means for putting the lever under a strain which through reaction on the two abutments holds the bars firmly to their seats. 110

4. In a beater roll, supporting elements carrying abutments and seats for fly bars; a pair of fly bars seated thereon, a clamping element comprising a lever having a trunnion extending from each side, one of said 115 trunnions entering an aperture in each bar, the lever being thus enabled to rock so as to bring its head end under one of said abutments, and a yoke adapted to span the two bars, having a set screw in the middle adapted to enter a socket formed in the tail end of the lever and whereby the lever may be put under a strain which draws the bars firmly 120 to their respective seats.

5. In a beater roll, supporting elements 125 carrying abutments and seats for fly bars; a pair of fly bars seated thereon, a clamping element comprising a lever having a

- trunnion extending from each side, one of said trunnions entering an aperture in each bar, the lever being thus enabled to rock so as to bring its head end under one of said 5 abutments, the head end of the lever carrying a set screw whereby the position of its tail end can be adjusted, said tail end being provided with a socket; a yoke which spans the bars and acts as an abutment for the 10 tail end of the lever, and having a set screw whose end enters said socket, and means for locking the set screw.
6. In a beater roll, supporting elements carrying abutments and having seats for fly 15 bars; a pair of fly bars, a pair of levers between them and trunnioned thereto, one lever being near each end of the bars, so that after the bars are in their respective seats the levers can be rocked and their outer 20 ends brought to bear under the abutments; and means for retaining the levers in position under the abutments and for putting them under a strain which, reacting through the trunnions, holds the bars firmly to their 25 seats.
7. In a beater roll, a shaft, two heads rigidly fixed thereon, each having an inwardly extending annular flange, the periphery of said heads having slots to act as seats for 30 fly bars; a pair of fly bars, a pair of levers between them, one near each end, attached to the bars by trunnions, so that the levers can be rocked to a position permitting them to clear the flanges on the heads as the bars 35 are being put in their seats, and then rocked to a position where their outer or head ends impinge the inside of the flanges; yokes spanning the two bars and confined between the inner edges of the bars and the 40 tail ends of the levers; and means for putting the levers under a strain which by bearing on the flanges and yokes reacts on the bars and holds them to their seats.
8. In a beater roll, supporting elements 45 having seats for fly bars, fly bars, clamping devices secured to the fly bars, set screws in the supporting elements which bear on said clamping devices and through them hold the bars to their seats, said set screws 50 having outwardly projecting extensions, wood fillers driven between the bars, said fillers having holes through which said extensions pass, and nuts screwed thereon to secure the wood fillers.
- 55 9. In a beater roll, a fly bar, a support having a seat for said bar, a beam, means for attaching the beam to the bar, two abutments on which the beam bears, said abutments being removed from the point at 60 which the beam is attached to the bar, one of the abutments being carried by the bar itself, and means for moving one of the abutments, thereby putting the beam under a strain which reacts on the bar through

said attachment and holds the bar to its 65 seat.

10. In a beater roll, a fly bar, a support having a seat for said bar, a beam, means for securing the beam to the bar at a point intermediate its ends, an abutment at each 70 end of the beam on which it bears, and means for moving one of the abutments, thereby putting a strain on the beam which reacts on the bar and holds it to its seat.

11. In a beater roll, a fly bar, a support 75 having a seat for said bar, a beam, means for attaching the beam to the bar, two abutments on which the beam bears, said abutments being at points removed from the point at which the beam is attached to the 80 bar, and means for moving one of the abutments, thereby putting a strain on the beam which reacts on the bar and holds it to its seat.

12. In a beater roll, a fly bar, a support 85 having a seat for said bar, a beam, means for attaching the beam to the bar, two abutments on which the beam bears, said abutments being removed from the point at which the beam is attached to the bar, one 90 of the abutments being the bar itself, and means for putting the beam under a strain which reacts on the bar through said attachment and holds it to its seat.

13. In a beater roll, two fly bars, a support 95 having seats for said bars, a beam, means for attaching the beam to the bars, two abutments on which the beam bears, said abutments being at points removed from the point at which the beam is attached to the bars, and means for putting the beam under a strain which will react on the bars through said attachment and hold the bars to their respective seats, the abutments being so situated and the attachment of the beam to the bars of such character that the strain is enabled to equalize 100 and act substantially the same on both bars.

14. In a beater roll, two fly bars, a support 110 having seats for said bars, a beam, means for attaching the beam to the bars, two abutments on which the beam bears, one of said abutments being carried by the bar, and means for moving one of the abutments, thereby putting the beam under a 115 strain which will react on the bars through said attachment and hold the bars to their respective seats.

15. A beater roll comprising a supporting element and fly bars spaced around said 120 element; means whereby a portion of said bars are secured to said element in pairs, each pair being attachable thereto and removable therefrom without affecting the security of all disturbing any other bars; 125 and means for securing one or more of the bars to said element snugly, so that said bar, or each bar if there are more than one,

can be attached thereto or removed therefrom without affecting the security of or disturbing any other bar.

16. A beater roll comprising a supporting element and fly bars spaced around said element; resilient means whereby a portion of said bars are secured to said element in pairs, each pair being attachable thereto and removable therefrom without affecting the security of or disturbing any of the other bars; and resilient means for securing one

or more of the bars to said element snugly so that said bars, or each bar if there are more than one, can be attached thereto or removed therefrom without affecting the security of or disturbing any other bar.

In testimony whereof I affix my signature in the presence of two subscribing witnesses.

ALBERT J. ALLISON.
